UNITED STATES PATENT OFFICE

JOHN A. JESSEN, OF WHITINSVILLE, MASSACHUSETTS, ASSIGNOR TO THE WHITIN MACHINE WORKS, OF WHITINSVILLE, MASSACHUSETTS, A CORPORATION OF MASSACHUSETTS

STOP MOTION FOR TWISTING MACHINES

Application filed August 2, 1929. Serial No. 383,065.

This invention relates to a stop motion particularly designed for use on machines in which two or more strands of yarn are twisted together to form a thread. In such machines, it is desirable to stop the feed of yarn whenever any one of the strands of yarn is broken, as otherwise a thread of less than the desired size and strength will be produced.

- 10 It is the general object of my invention to provide an improved mechanism for automatically stopping the feed of yarn to any spindle whenever any one of the yarn strands associated therewith is broken.
- 15 A further object is to provide a stop motion which will also stop the machine for a thread broken below the feed rolls, but which will not become operative upon slight slackness of the twisted thread, such as is caused by the 20 shutting down of the machine.

My invention further relates to arrangements and combinations of parts which will be hereinafter described and more particularly pointed out in the appended claims.

25 A preferred form of the invention and a modification thereof are shown in the drawings in which

Fig. 1 is a sectional side elevation of parts of a twisting machine having my improved 30 stop motion applied thereto;

Fig. 2 is a plan view of certain parts, looking in the direction of the arrow 2 in Fig. 1;

Fig. 3 is a plan view of my improved stop motion on an enlarged scale;

35 Fig. 4 is a side elevation of the stop motion showing the operation of the invention when a thread breaks between the spool and the feed rolls;

Fig. 5 is a view similar to Fig. 4 but showing the parts when the machine is not in operation;

Fig. 6 is a side elevation showing the operation of the invention when the twisted thread breaks below the feed rolls;

45 Fig. 7 is a sectional side elevation of parts of a twisting machine having a modification of my invention applied thereto;

Figs. 8 and 9 are enlarged side elevations, 50 illustrating the operation of the mechanism shown in Fig. 7; and

Fig. 10 is a detail view looking in the direction of the arrow 10 in Fig. 6.

Referring to Figs. 1 to 6, I have illustrated the preferred form of my invention as embodied in a twisting machine having a frame 55 10, spindles 11 by which bobbins B are rotated, a ring rail 12 supporting rings 13 on which travellers 14 are mounted, a creel 15 provided with rods 16 on which yarn spools S are rotatably mounted, and feed rolls 19 and 60 21 by which two or more strands of yarn Y are fed to a yarn guide 22 from which they pass to the traveller 14 and bobbin B. All of these parts are of the usual type and in themselves form no part of my present invention. 65

My improved stop motion, as shown in the drawings, is designed for use in twisting thread from two strands of yarn for each thread, but may be readily extended for use in connection with the twisting of thread 70 from three or more yarn strands.

I provide a separate stop motion unit for each spindle 11 and bobbin B. Each unit is mounted on a stand 20 adapted to be clamped to a supporting bar 25 extending 75 longitudinally of the machine and mounted on brackets 23 projecting rearwardly from the feed roll stands 24. Each stand 20 is provided with upwardly projecting portions 26 and 27. A fixed clamping bar 28, preferably of rectangular cross section, is secured to the projecting portion 26 by a clamping nut 29 (Fig. 2). A thread guide 30, commonly of porcelain, is similarly secured to the portion 27 by a binding nut 31. 80

A second and movable clamping member 34 is pivoted on a screw 35 secured to the stand 20, and the sharply beveled clamping end thereof is adapted to swing into engagement with the fixed clamping member 28, as 85 indicated in Fig. 4.

The left hand end 36 of the member 34 is substantially heavier than the clamping end, the weight being increased by downwardly extending wings 37 at each side thereof. The flat upper surface of the portion 36 is slotted, as indicated at 38 in Fig. 3, to permit swinging upward movement of indicating members 40 of U-shaped section and loosely pivoted on the screw 35 previously described. 90 100

Yarn-engaging hooks 42 are mounted in the indicating members 40, which are also provided with wings or extensions 44 adapted to engage a stud 45 in a latch 46 pivoted at 47 on the stand 20. A third indicating member 50, also of U-shaped section, is loosely pivoted on the screw 35 and is also provided with a wing or extension 52 (Fig. 5) adapted to engage the stud 45.

10 A rod or arm 53 is secured to the end of the member 50 by a screw 54 threaded into the end of a stud 55. The arm 53 is provided with an offset porcelain guide 56, adapted to rest on the twisted thread T. The stud 55 has a reduced lower end 57 which is threaded to receive a counterweight 58.

15 A bracket 60 (Fig. 4) is clamped to the stand 20 and provides a support for thread guides 62 by which the separate strands of 20 yarn are guided to the stop motion.

20 The thread guides 62 are preferably slotted downwardly and communicate with openings 64 (Fig. 10) in the under side of the bracket 60, by the use of which the yarn is easily and 25 conveniently inserted in the guide 62.

25 The normal running position of the parts is indicated in Fig. 1, with the yarn strands Y passing through the guides 62 and between the fixed clamping member 28 and the movable clamping member 34, then over the yarn guide 30 and under the hooks 42 forming the upper ends of the separate indicating members 40. The yarn then passes over the upper feed roll 21, around the lower feed roll 19, 35 and under the member 56 to the thread guide 22, from which point it is drawn downward and wound on the bobbin in the usual manner.

30 With the parts thus arranged, the indicating members 42 are each supported by a separate yarn strand Y between the guide 30 and the upper feed roll 21, and the indicating arm 53 is supported by the thread T which engages the member 56 between the 45 lower feed roll 19 and the thread guide 22.

35 The clamping member 34 is provided with a depending hook 65 adapted to be engaged by a corresponding hook 66 on the latch 46. The yarn Y passes freely between the fixed 50 clamping member 28 and the movable clamping member 34 so long as the member 34 is latched in the position shown in Fig. 1. If, however, one of the yarn strands Y breaks, the corresponding hook 42 and indicating member 40 will drop to the position indicated at the left in Fig. 4, allowing the wing portion 41 thereof to engage the stud 45 and withdraw the latch 46, as also shown in Fig. 4.

40 As soon as the latch 46 is withdrawn, the excess weight at the left hand end of the clamping member 34 causes the same to rock to the position indicated in Fig. 4, clamping all of the yarn strands Y between the members 28 and 34 and effectively preventing any 45 further feed of the yarn to the feed rolls 19.

and 21. Similarly, if the thread T breaks below the feed roll 20, the arm 53 will swing downward, carrying the attached wing 52 in contact with the stud 45, withdrawing the latch 46, causing the clamping of the yarn strands, and preventing yarn feed to the feed rolls. 70

If, however, the thread T is merely slackened as by the shutting down of the machine, the arm 53 will swing slowly downward to the position shown in Fig. 5, which movement is not sufficient to engage the stud 45 and release the latch 46. The weight 58 is used to partially offset the weight of the arm 53 and guide 56, and may be adjusted as desired. 75

It is desirable to be able to raise the hooks 42 and the member 56 to normal running position and to hold them there during the threading operation. For this purpose I provide a crank 70 (Fig. 5) extending crosswise 80 of the stop motion and having a bearing 71 in the stand 20 and also having a handle 72 at the side of the stand.

By swinging the handle 72, the crank 70 is brought under the wing portions of the indicating members 40 and 50 and moves them all to the normal running position shown in Fig. 1, in which position they will be retained until the handle 72 is returned to its inoperative position, with the crank 70 engaging a stop pin 74 (Fig. 5).

In Figs. 7, 8 and 9 I have shown a simplified construction of my improved stop motion which is operative only upon breakage of the thread T below the feed rolls. 100

The parts are essentially similar to those used in the form previously described and comprise stands 80 supporting a rod 81 on which arms 82 are secured in spaced relation. Each arm 82 is provided with a supporting plate 83 on which a fixed clamping member 84 is secured. A movable clamping member 85 is pivoted at 86 and has a hook-like projection 87 engaging a hook 88 formed on a latch 89. A thread-engaging member 90 is mounted at the lower end of an arm 91 which is secured to an indicating plate 92, loosely pivoted on the stud or screw 86, and having an arm 94 adapted to engage a projection on the latch 89. 110

When the thread T breaks, the arm 91 swings downward, its arm 94 engaging the latch 89, and withdrawing the same from the hook 87 on the movable clamping member 85. The clamping member 85 then moves upward to the position indicated in Fig. 8, preventing the delivery of any further thread or yarn to the feed rolls. 120

If the thread is merely slackened gradually instead of breaking, the arm 91 will swing down slowly to the position indicated in Fig. 9, and the latch 89 will not be moved to such an extent as to release the clamping member 85. Consequently the delivery of yarn will not be prevented when the threads are merely 125 130

slackened by the shutting down of the machine.

The operation of the mechanism shown in Figs. 7, 8 and 9 is thus substantially identical with that shown in Figs. 1 to 6, but the mechanism is of more simple construction and has a more limited range of utility.

Having thus described my invention and the advantages thereof, I do not wish to be limited to the details herein disclosed, otherwise than as set forth in the claims, but what I claim is:—

1. In a twister stop motion, a stand, a horizontally extending clamping bar of angular cross section fixed thereon, a movable clamping bar pivoted thereon and movable by its own weight to clamping position, said movable bar having an angular clamping edge, a latch to hold said movable bar in inoperative position, and means separately engaging different yarn strands and effective to withdraw said latch upon breakage of any strand, the end of said released movable bar engaging a flat face of said fixed bar with a wedging gripping action on the yarn.

2. In a twister stop motion, a stand, a horizontally extending clamping bar of angular cross section fixed thereon, a movable clamping bar pivoted thereon and movable by its own weight to clamping position, said movable bar having an angular clamping edge, a latch to hold said movable bar in inoperative position, and means separately engaging different yarn strands and effective to withdraw said latch upon breakage of any strand, the end of said released movable bar engaging a flat face of said fixed bar with a wedging gripping action on the yarn, said yarn engaging means being movable downward to an intermediate inoperative position by gravity upon thread slackness, and being further movable by inertia beyond such inoperative position to render said clamping members operative upon thread breakage.

45. 3. In a twister stop motion, a stand, a horizontally extending clamping bar of angular cross section fixed thereon, a movable clamping bar pivoted thereon, said bar having a weight effective to move the bar to clamping position, said movable bar having an angular clamping edge, a latch to hold said movable bar in inoperative position, yarn engaging means connected to said bar and effective to withdraw said latch upon breakage of the yarn, and means adjustably mounting said weight on said bar whereby the weight may be positioned to partially offset the weight of the yarn engaging means, said movable bar, when released, being effective to engage the fixed bar with a wedging gripping action.

In testimony whereof I have hereunto affixed my signature.

JOHN A. JESSEN.
